Primary Examiner — Mark Goodwin(74) *Attorney, Agent, or Firm* — Dickinson Wright PLLC(57) **CLAIM**

The ornamental design for a combined sprayer and spreader with sulky, as shown and described.

DESCRIPTION

FIG. 1 is a top front perspective view of the combined sprayer and spreader with sulky showing our new design;

FIG. 2 is a top rear perspective view thereof;

FIG. 3 is a top view thereof;

FIG. 4 is a front view thereof;

FIG. 5 is a rear view thereof;

FIG. 6 is a side view thereof; and,

FIG. 7 is an opposite side view thereof.
